CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with graphical user interface showing our new design according to a first embodiment of the invention.

FIG. 2 is a front view of a display screen or portion thereof with graphical user interface according to a second embodiment of the invention.

FIG. 3 is a front view of a display screen or portion thereof with graphical user interface according to a third embodiment of the invention; and,

FIG. 4 is a front view of a display screen or portion thereof with graphical user interface according to a fourth embodiment of the invention.

The dot-dash broken line showing of the display screen or portion thereof forms no part of the claimed design.

The dash-dash broken lines show portions of the graphical user interface that form no part of the claimed design.
